ELECTRIC WELDING.

1,181,227.

Specification of Letters Patent.

Patented May 2, 1916.

Application filed April 16, 1915. Serial No. 21,852.

To all whom it may concern:

Be it known that I, OTIS ALLEN KENYON, a citizen of the United States, residing at River View Manor, Hastings-upon-Hudson, 5 in the county of Westchester and State of New York, have invented new and useful Improvements in Electric Welding, of which the following is a specification.

This invention relates to electric welding, and has for its object to increase the energy efficiency of electric arc welding.

The electrical characteristics of the arc are such that when operated from a source of constant potential it is necessary to connect a ballast resistance to regulate the current so that it will tend to remain constant. In operation, the resistance characteristics of an arc are as follows:—The resistance of the arc decreases with increasing current, 15 and increases with decreasing current, therefore with constant impressed potential the arc is unstable and cannot be maintained. A constant and relatively large ballast resistance connected in series with the arc will produce a drop of E. M. F. proportional to the current, therefore, the combination as a whole will tend toward constant current with a constant potential, because when the resistance of the arc decreases the 20 current tends to increase and every increase in the current will cause a greater drop in the ballast resistance and thus reduce the E. M. F. across the arc tending to prevent further increase in current. On the other hand an increase in the resistance of the arc 25 will tend to decrease the current, and a decrease in current will cause less drop through ballast resistance and therefore allow an increase in E. M. F. across the arc, thus working against any decrease in current. The ideal condition with the above described welding circuit is approached by increasing indefinitely the generator E. M. F. and the ballast resistance, that is, the greater 40 the ballast resistance the more stable the arc.

Economically considered the ballast resistance method is very undesirable because the E. M. F. consumed in the ballast resistance is a dead loss and any attempt to reduce this loss is accompanied by a corre-

sponding sacrifice in the stability of the arc.

Another system of electric supply for welding is the constant-current system. However it is only in limited use because up to the present time constant-current generators have only been used in the operation of one welding arc and where more than one arc is to be used constant-potential machines with ballast resistors must be resorted to. It is my purpose to provide means by which the constant current can be supplied to several welding arcs in series without in any way interfering with the free operation of the arcs by the welders. 65 To accomplish this I provide a portable controller adapted to be switched into the main line, the controller comprising a low-resistance, or by-pass, line and an arc line in parallel with each other and in series 70 with the main line, and two solenoid windings, one in series with the arc line and the other in shunt therewith, each winding adapted to control a contact bridge when current passes therethrough. 75

In the accompanying drawings: Figure 1 is a diagram illustrating a special relay or controller adapted to carry out my invention. Fig. 2 is a diagram illustrating an electric welding plant, and showing three controllers switched into the main line. Fig. 3 is a diagram illustrating an electric welding plant, having two main circuits and showing various arrangements hereinafter described. 80 85

Preferably I use a generator that will produce a constant current that can be adjusted by means of an ordinary field rheostat for any value within the maximum limit of the machine. In Fig. 2 a generator proper G, an automatic regulator R and an exciter E are diagrammatically represented. This machine may be so designed that it will respond instantly to changes in the resistance of the external circuit, and maintain a 90 practically constant value of current at all times. However any constant-current generator may be used. 95

The portable relay or controller C is adapted to preserve the continuity of the 100

main circuit at all times independent of the manipulation of the arc. A controller C is used in connection with each welding arc, and is adapted to be plugged across the terminals of a switch S in the main circuit, as shown.

When the switch S is opened the current is simply by-passed through the controller without interrupting the continuity of the circuit, the only change being a slight increase in resistance. From the positive terminal of the switch, current passes through resistance 10, Fig. 1 across bridge 11, normally closed by spring 12, through wires 13 and 14 to the minus side of the switch. The path 10, 11, 13 and 14 then forms a portion of the main circuit. When the arc A is struck, current passes from the positive terminal of the switch through the arc line 15, and arc A to line 16 and series solenoid winding 17, through wires 13 and 14 to the minus side of the switch. Series winding 17 controls bridge 11 against the action of spring 12 when current passes through said winding. It will be seen that the arc line 15, A, 16, 17, is in parallel with the low-resistance path 10, 11. If the resistance in the low-resistance path is sufficient to cover the drop of E. M. F. in the series relay 17 and the contact resistance of the arc A, there is no need of a special resistance 10, and in such case resistance 10 may be omitted.

The current passing through the series winding 17 opens the bridge 11, thus inserting the arc line in series with the main line without interrupting the continuity of the circuit, and with no change in resistance except a slight decrease first, followed by an increase as the welder draws his arc. A shunt winding 18 is inserted in parallel with the arc line. When sufficient current passes through the winding 18, it controls bridge 19, normally maintained open by spring 20. When a welder withdraws from the circuit he does so by lengthening his arc and as the arc lengthens the E. M. F. across it increases, and more and more current is shunted through the winding 18 until a point is reached where the mechanical resistance of spring 20 is overcome and the contact bridge 19 is closed, then the current from the arc passing through the bridge 19, short circuits winding 17, and allows spring 12 to close bridge 11. This allows the current to pass direct through resistance 10, bridge 11, and wires 13, 14, and practically short-circuits the arc and causes it to drop out of the circuit without interrupting the continuity thereof.

From the above description it is evident that any number of welders within the E. M. F. limit of the electric machine may connect into the circuit by means of these controllers C, see Fig. 2, as long as each welding job is insulated from the others; and in spe-

cial cases two men can weld on the same job by allowing one to connect his welding pencil to the positive side of the circuit and the other one to connect to the negative side.

In operating with one arc the controller C is just as necessary as when operating with several on account of the fact that the generator may be capable of furnishing E. M. F. enough to take care of several arcs. Supposing the generator were capable of furnishing E. M. F. for say six arcs and with a liberal excess for stabilizing purposes, when operating with one arc the welder would have available from nothing up to 300 volts, depending on how long an arc he drew. An arc of 150 amperes and 300 volts would produce many times more heat than is either necessary or good for welding. Therefore, a controller exactly the same as used in plants where a number of arcs are in operation is necessary to cut out the arc as soon as the voltage rises to a predetermined value. In this way the arc is automatically protected from any voltage greater than said predetermined amount and yet it has the stability inherent to the high voltage. Also it is possible to fix definite limits to the amount of heat that can be applied by the welder in any given case independent of the number of welders in circuit. The current being adjusted at the generator is automatically maintained at the constant value, and the voltage which each welder can use may be set by adjusting his particular controller as for instance by adjusting the spring 19 or the winding 18 or both.

In large installations a more flexible arrangement can be provided by using two or more generators similar to the one above-described, and running two or more circuits throughout the working area. A system of this kind arranged for two generators is shown in Fig. 3. At station 1, one man could weld with the current produced by one of the generator units, and at station 2 a man could weld with current produced by a second generator unit. At station 3 connections are shown whereby one man could weld with the sum of the currents from both the generators. At station 4 connections are shown whereby two men can weld on the same piece, each using current from a different generator.

The current in each generator may be set at any value desired each independent of the other. If both generators are set at the same value, then there are two values of current always available in the shop, that of one machine and double. If the machines are set at different values, there are three values always available, that of each machine and the sum of the two. A perfectly flexible adjustment of the current taken by each arc independent of all others may be attained by an adjustable shunt 21, across the

terminals of the controller C. The capacity of this shunt must be sufficient to carry the difference between the maximum current in the circuit and that required at the particular controller where it is installed.

The circuits may be increased to any desired number by adding more machines to the plant. An installation of two or more generators, such as shown in Fig. 3, economically considered, is cheaper in first cost than an installation of the constant-potential type capable of doing the same amount of work, and the cost of operation of such a plant is very much less on account of the complete elimination of ballast resistance. Generators of this type may be connected in parallel and when so connected will operate as one machine for a constant current, independent of the value of resistance in series up to the E. M. F. limit of the machine.

The controllers herein described have been used by me on constant-potential circuits for limiting the voltage across the arc and for operating two or more arcs in series; therefore, while the controller is especially adapted for use in constant-current circuits it may also be advantageously employed on constant potential circuits of higher voltage than that required for successful operation of an arc. For instance, it is ordinary practice to employ generators of from 60 to 75 volts in constant-potential welding plants, while with the controllers of the type herein described it is possible to operate two arcs in series from the ordinary 125-volt lighting circuits, thus avoiding entirely the necessity of installing a special welding generator. When 220 volts are available more arcs may be operated in series in the same manner. Therefore, it should be distinctly understood that the controller herein described is not in any way limited to application on constant-current circuits. Nor do I limit myself to the specific form of controller, which is herein set forth only as the preferable means for accomplishing the desired result.

I claim as my invention:—

1. In electric welding, a main circuit, a plurality of welding arcs adapted to be connected in series in said main circuit, and means for maintaining the conductance of the main circuit sufficiently uniform to prevent the interference of any one arc with any of the others.

2. In electric welding, a main circuit, a plurality of welding arcs adapted to be connected in series in said main circuit, means for maintaining the conductance of the main circuit sufficiently uniform to prevent the interference of any one arc with any of the others, and means for limiting the impressed voltage.

3. In electric welding, a main circuit, a

plurality of welding arcs adapted to be connected in series in said main circuit, means for maintaining the conductance of the main circuit sufficiently uniform to prevent the interference of any one arc with any of the others, and automatic means for limiting the impressed voltage.

4. In electric arc welding, a main line, an arc line connected in parallel with a portion of the main line, in combination with means adapted to open the main line between the connections of the arc line when the arc is struck, and to close the main line before the resistance in the arc line reaches a predetermined amount.

5. In electric arc welding, a main line, an arc line connected in parallel with a portion of the main line, in combination with means adapted to automatically open the main line between the connections of the arc line when the arc is struck, and to automatically close the main line before the resistance in the arc line reaches a predetermined amount.

6. In electric arc welding, a main line, an arc line connected in parallel with a portion of the main line, in combination with electro-responsive means for opening the main line when the arc is struck, and to shunt the current from the arc line to the main line when the resistance in the arc line reaches a predetermined amount.

7. In electric arc welding, a main line, an arc line connected in parallel with a portion of the main line, a series relay in the arc line adapted to open the main line between the connections of the arc line when the arc is struck, and a shunt relay in parallel with the arc line and adapted to short circuit the series relay to permit the main line to close when the resistance in the arc line reaches a predetermined amount.

8. In electric arc welding, a main line, in combination with a controller adapted to be switched into the main line, said controller comprising two lines in parallel with each other and each in series with the main line, the first line in the controller being normally closed, the second including the welding arc, and means for opening the said first line when the arc is struck and for closing the first line before the resistance in the arc line reaches a predetermined amount.

9. In electric arc welding, a main line, in combination with a controller adapted to be switched into the main line, said controller comprising a low resistance line normally closed in series with the main line, an arc line in series with the main line, and means dependent upon current in the arc line to open the low resistance line, and means for shunting the current from the arc line when the resistance therein reaches a predetermined amount.

10. In electric arc welding, a main line,

a controller adapted to be switched into the main line, said controller comprising a low resistance line normally closed in series with the said main line, an arc line in series with the main line and provided with a series relay adapted to open the low resistance line when the arc is struck, and a

shunt relay in parallel with the arc line adapted to short circuit the series relay when the resistance in the arc line reaches 10 a certain amount.

In testimony whereof I have signed my name to this specification.

OTIS ALLEN KENYON.
